UNITED STATES PATENT OFFICE.

ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

PRESSING MACHINE.

Application filed June 18, 1924. Serial No. 730,869.

This invention relates to pressing machines such as garment and laundry pressing machines, and has for its object a particularly simple mechanism for transmitting the power from the power member to the movable pressing element or head, by which mechanism the movable element or head must be moved preliminarily toward a closed position before the motion transmitting mechanism is brought into position to effectively transmit the power from the power member, and by which mechanism dead centers in the motion transmitting mechanism are eliminated or the effect of such dead centers avoided.

This invention consists in the novel features and in the combinations and constructions hereinafter set forth and claimed.

In describing this invention reference is had to the accompanying drawings in which like characters designate corresponding parts in all the views.

Figure 1 is the side elevation of a machine embodying my invention.

Figure 2 is a detail view of the link which includes the endwisely movable sections.

Figure 3 is a view similar to Figure 1, parts being omitted showing the position of the parts when the press is in closed position.

Figure 4 is a similar view showing the position of the parts when such parts are in neutral or dead center position.

This pressing machine comprises generally cooperating pressing elements, one of which is movable toward and from the other, and actuating means including a power member and connections between the power member and the movable element, normally arranged out of effective position to transmit the power of said member, and shiftable into effective position by a preliminary movement of the movable element toward a closed position independently of the power member.

Such connections include a pair of links, one of which is pivotally connected to the frame independently of the power member and the other of which is pivotally connected to the power member, these links normally extending in the same general direction and located to have a parallelogramlike action when the brace is open, and being movable toward a converging position when the brace is preliminarily closed.

One of such links includes endwisely movable sections and a spring for restraining such endwise movement.

The numeral 1 designates the frame, which may be of any suitable form, size and construction, it being here illustrated as including one or more legs or pedestals 3, 4. The numerals 4 and 5 designate respectively the cooperating pressing elements. The element 4 is shown as a stationary buck mounted on a bracket 5, which in turn is mounted upon the frame 1.

The movable element 5 is a head here shown as carried by a yoke or lever 7 pivoted at 8 between its ends to a standard forming an extension of the rear leg of the frame. The head 5 is carried on the front arm of the lever or yoke, and a suitable counter-weight 10 is carried on the rear arm of the lever.

11 is the power member, it being usually a lever pivoted between its ends at 12 to the frame near the base thereof, and nearly in the vertical line with the pivot 8, this lever being actuated by a power mechanism. The connections between the power member and the movable element 5 or the yoke or lever 7, comprises toggle mechanism including a link 13 pivoted at 13^a to the rear arm of the yoke or lever 7. A second toggle link 14, is pivoted at 15 to the link 13 and to the frame, it being preferably pivoted to the same pivot 12 that the power lever 11 is mounted on, and a third link 16 is pivoted to the rear arm of the lever 11 and to one of the former links. The link 16 normally extends horizontally in the same general direction as the link 14, but diverges from the link 14.

The link 16 is pivoted at its rear end to an extension 17 of the link 13, which extension projects below or beyond the point 15 or toggle links 13, 14. This link 16 is movable upwardly and forwardly during the preliminarily closing movement of the press head, and assumes a converging relation with the link 14; such movement being due to the fact that the link 16 is shorter than the link 14. The link 16 is connected to one of the parts by a lost motion connection, here shown as a pin-and-slot connection. The pin 18 is shown formed on the extension 17 and the slot 19 in the link 16. Owing to the arrangement of the second and third links, that is, the links 14 and 16 and the extension 17,

these links 14 and 16 have a parallelogram-like action.

One of the links 14 and 16 is composed of sections having relative endwise movement, and a spring for resisting such movement. In this embodiment of my invention, the link 16 is shown as formed of sections 20 and 21 movable relatively to each other and a spring for resisting such movement. The sections 20 and 21 are slidably mounted upon a rod 22 arranged in axial passages in these sections and the spring encircles the rod and thrusts at its ends against the sections.

15 In operation during the preliminary closing of the press head by pulling down on the handle 24 on the yoke, the toggle links 13 and 14 are moved toward straightened position, and during such movement the link 16 is lifted from a horizontal to an upright position moving the pin 18 toward the lower end of the slot 19. After the links 13, 14 have been straightened or nearly so by such preliminary closing of the head 5, 20 the power lever 11 is actuated and the motion thereof transferred upwardly through the link 16 and extension 17 of the link 13, to move such links 13 and 14 toward the dead center line of the links 13, 14 which 25 constitutes a toggle. However, after the power is applied to the lever 11 before the press has been preliminarily closed or while 30 the head 5 is in an intermediate position the lever 16 will merely idle and not transfer 35 any movement.

40 There is a dead center region of the links 13, 14 and 16 where the power, if applied, does not transmit the motion but tends to stall the machine or the motor, or burn out the motor or the fuses in the service wires.

45 In order to eliminate such stalling and other results the link 16 is formed of relatively movable sections and, therefore, when the links 13, 14 are at such a dead center or neutral point, the spring 23 compresses and no motion is transferred to the head. The arrangement of the links 13, 14 and 16 is such that the head must be brought to the safety first position, where the head practically touches the work on the buck 4. It is when the head is not brought down quite to this safety first position that the spring 23 acts to avoid stalling of the mechanism.

55 The means for applying power to the lever
11 may be of any suitable form, size and con-
struction, and includes generally a rotatable
cam shaft 25 actuated by a constantly run-
ning electric motor 26, which is connected to
the cam shaft 25 through gearing and a peri-
odic clutch located within the housing 32.
60 The shaft is provided with a cam or eccen-
tric 30 which coacts with the face 31 on
the outer end of the lever 37. The peri-
odic clutch is thrown in by hand through
65 suitable mechanism including the handle 41,

mounted on a rock shaft 41^b having an arm 43 thereon coacting with a lever arm 44, which acts to shift the clutch section to its position.

For a full description of this clutch mechanism reference is had to my pending application Sr. No. 683,151, filed December 28, 1923. 70

In the complete operation of the machine, assuming the parts are in a position shown in Figure 1, the operator preliminarily closes the press by pulling down on the handle 24 and then depresses the handle 41 to throw in the clutch whereupon the shaft 25 makes a half revolution from the position shown in Figure 1 to that shown in Figure 3. In making such half revolution the cam depresses the power member 11 and after the links 13, 14 have been nearly straightened by the preliminary closing movement, the power of the lever 11 will be applied to the head 5 to apply final pressure or completely close the press. To open the press the operator depresses the handle 41^a to again throw in the clutch, and the shaft 25 makes another half revolution permitting the head 2 to open under the influence of the counterweight 10 and the links 13, 14. 75 80 85 90

When the power is applied before the preliminary closing movement is completed, the power lever and links merely idle, and after the operator has released his hold on the handle 24, the head 5 will open under the influence of the counter-weight. 10

After the power is applied and the links are at the dead center point or region, the spring 23 of the links 16 will yield and no power will be transmitted, it being understood that when at this dead center point 105 the link 13 and lever 7 are stalled or will not move, but as the power lever 11 is being moved by the cam and hence actuating the links 16 something has to give, as the pin 18 comes to the lower end of the slot 110 19, and the link 16 is provided to yield or give under these conditions.

In the event the operator operates the handle 41^a to throw the clutch in before the head has been preliminarily closed, or before it has been brought down to a position close to the buck 4 or the work thereon, the shaft 19 makes a half revolution and depresses the lever 11, but on account of the arrangement of the links 13, 14 and 16, the link merely idles, and transmits no motion. However, the sequence of the mechanism is now upset and in order to restore the sequence the handle 41^a must be again operated to cause the shaft 25 to make another idle half revolution. 115 120 125

What I claim is:

1. In a pressing machine, a frame, co-operating pressing elements supported by the frame and one being supported to move 130

toward and from the other, and means for actuating the movable element comprising a power member and toggle mechanism between the power member and the movable element, the toggle mechanism comprising a link pivotally connected to the movable element, a second link pivoted to the first link and to the frame, and a third link pivoted to the power member and to one of the former links, one of said links comprising sections having an endwise movement relative to each other and a spring for resisting such endwise movement.

2. In a pressing machine, a frame, co-operating pressing elements carried by the frame, one being supported to move toward and from the other, and means for actuating the movable element including a power member and toggle mechanism comprising a link pivotally connected to the movable element, a link pivotally connected to the first link and to the frame and a connection between the power member and the first link comprising a third link pivoted to the power member and to the first link, the third link

including sections movable endwise relatively to each other and a spring for resisting such endwise movement.

3. In a pressing machine, a frame, co-operating pressing elements supported by the frame, one being supported by the frame to move toward and from the other, and actuating means comprising a power member and connections between the power member and the movable element including parts normally out of effective connection with the power member and arranged to be moved into effective connection by a preliminary closing movement of the movable element independently of the power member, one of said parts including sections having movement relatively to each other and a spring for resisting such movement of the sections in one direction.

In testimony whereof, I have hereunto signed my name, at Syracuse, in the county of Onondaga, in the State of New York, this 20th day of May, 1924.

ALBERT B. CLISSON
